US0D1071093S

(12) **United States Design Patent** (10) Patent No.: **US D1,071,093 S**
(45) Date of Patent: ** Apr. 15, 2025

(54) **FAUCET**

(71) Applicant: **GLOBE UNION INDUSTRIAL CORP.**, Taichung (TW)

(72) Inventors: **Yi-Shan Chiang**, Taichung (TW);
Ya-Chieh Lai, Taichung (TW);
Chun-Yi Tu, Taichung (TW); **Shi-Chen Lai**, Taichung (TW); **Meng-Chun Yen**, Taichung (TW)

(73) Assignee: **GLOBE UNION INDUSTRIAL CORP.**, Taichung (TW)

(**) Term: **15 Years**

(21) Appl. No.: **29/914,656**

(22) Filed: **Oct. 20, 2023**

(51) LOC (15) Cl. **23-01**

(52) U.S. Cl.

USPC **D23/242**

(58) **Field of Classification Search**

CLAIM

The ornamental design for a faucet as shown and described.

DESCRIPTION

FIG. 1 is a perspective view of a faucet showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The portions shown in broken lines form no part of the claimed design.

1 Claim, 7 Drawing Sheets
